[57]

ABSTRACT

The invention relates to a system for conveying information from a plurality of stations, particularly stations associated with textile machines such as looms, to a recorder such as a human operator or a computer. A plurality of address lines connect each textile machine station to each other textile machine station and carry coded address signals, each address line carrying a digit of a binary number representing the particular station chosen for interrogation, and at least a single return line connects each station to each other station and to the recorder to convey information gathered at the station to the recorder. In one embodiment, address signals designating a particular loom station are sent by an interrogator to each loom and the loom so chosen by the address signals responds by applying electrical information signals containing information on the condition of the chosen loom to the return line or lines. The information signals on the return line or lines are sequentially examined and the interrogation ended if certain information is present.

LOOM STOP DATA COLLECTION SYSTEM

DESCRIPTION OF PRIOR ART AND SUMMARY
OF THE INVENTION

This application is a continuation-in-part of application Ser. No. 746,962, filed July 23, 1968, for Loom Stop Data Collection System, now abandoned.

The invention relates to a system for conveying information from a plurality of stations to a recorder.

In any factory with a number of independently operating machines and particularly in a textile mill it is desirable to be constantly aware of which machines are in operation, as well as which machines are not. This knowledge enables the factory mill supervisors to gauge the future material requirements of each respective machine as well as to judge accurately present and future overall and individual outputs. In a textile mill, this information is especially important since the pay of the workers operating the machines is usually related to the amount of material produced and this can be determined from the total operating time of each machine since the output of each machine as a function of time is known. Also, in the event of stoppage it is desirable to know the cause thereof so that the proper repairmen can be dispatched as required, workloads rearranged to compensate for the break-down, etc.

In the past, pick counters mounted on each individual textile machine have been employed to record the number of loom running cycles. However, such devices provide data which must be manually and periodically read and which does not supply an immediate indication of loom stoppage nor the reason thereof.

Other systems in the past have utilized an interrogation system whereby a loom is ordered to reply by signals sent from an interrogator to the loom and the reply information then conveyed back to the interrogator on a number of return lines which connect just that machine and the interrogator. One such system is described in the Adams et al. U.S. Pat., No. 3,226,726.

In contrast, the present invention relates to an information conveying system whereby all of the machines are connected to each of a number of interrogation or address lines and all of the machines to a number of return lines. Utilizing the same interrogation and return lines for all of the machines greatly reduces the number of wires required to convey information, since only one return wire is required for each type of information being returned to the interrogator and since a plurality of address lines can serve a much larger number of machines. This system also displays flexibility in that the additional conditions can be added without altering the basic interrogation system, since each additional condition sensed merely requires the addition of a single return wire connecting to all of the looms and the interrogator. Also the system can be readily expanded to serve more looms simply by the addition of additional interrogation lines, each line added roughly doubling the number of looms which can be handled. In addition, all of the address lines and return lines can be grouped in a single shielded cable so that signal distortions in the normally electrically noisy textile machine or factory environment are minimized.

In one embodiment, a multi-level addressing system is employed whereby a human operator or computer first addresses a master station having associated with it

a number of individual data stations. The master station thus addressed then enables a second master station or the associated data stations to receive a second address identifying a master or data station among those associated with the first master station. In this fashion and individual data station is identified by a system requiring fewer and simpler components than otherwise required.

This invention can be employed with a human operator or a computer or other recorder. When used with a computer, the computer then chooses the machines to be interrogated, receives the raw data, and works it into any form which is convenient. A computer also can interrogate a very large number of machines at a frequency which is great enough so that the operation and conditions of all the looms at any given time is effectively available. In addition, the computer can provide valuable information and predictions such as an accurate prediction as to when the warp beam will run out on each loom thereby minimizing time due to warp stops.

The present invention also relates to a system whereby the loom stations notify the computer or human operator when stoppage occurs and communicate the cause thereof. In one embodiment a loom station supplies its binary address to a computer via the interrogation or address lines when stoppage occurs and then applies a signal to one of a number of return lines indicating the reason for the stoppage. When the stoppage ends, the address is once again supplied to the address lines without accompanying signals on the return lines.

In the specific embodiment discussed herein, the four common causes of loom stoppage which account for the vast majority of loom stops — filling stops, warp stops, warp out stops, and mechanical breakdowns — are checked. In addition the sensing apparatus associated with detecting filling and warp stops has the memory capability of retaining information so that it can be determined if a filling or warp stop has occurred between interrogations regardless of whether or not it has ended before the interrogation.

Also, the present invention can be used with a manual interrogation system and includes a method of sequentially examining the loom data received on the return lines and logical apparatus for performing this function. By this method each of the looms is checked sequentially to determine whether it is in operation and if it is, the interrogator, either human or computer, passes on to check the next loom. Only if the machine is not operating are the lines which carry information on the cause of stoppage sequentially checked. In the detailed embodiment, the warp out stop sensor line is checked first, followed by the filling stop sensor line and the warp stop sensor line. The filling upon discovery of that fact. However, if none of the three causes is determined to be the cause of stoppage, then the stoppage is assumed to be due to mechanical failure and is recorded as such.

Other objects and advantages of the system will be apparent from reading the following detailed description.

65 BRIEF DESCRIPTION OF THE DRAWINGS

FIG.1 shows a loom control and interrogation system for producing address signals identifying the loom

chosen for interrogation and for receiving information signals from the loom;

FIG. 2 shows a loom station which responds to an address signal by applying information signals to return lines;

FIG. 3 shows a card of recording loom information;

FIG. 4 shows an interrogating system having a loom station with logic elements arranged to apply signals to the return lines;

FIG. 5 shows a logic sequencing network for dealing with the information on the return lines;

FIG. 6 shows another interrogating system whereby the loom station notifies the computer when stoppage occurs;

FIG. 7 shows yet another interrogating system whereby the loom station notifies the computer when stoppage occurs;

FIG. 8 shows a multi-level address system for addressing a loom chosen for interrogation; and

FIG. 9 shows a master station for use in the system of FIG. 8.

DETAILED DESCRIPTION OF THE DRAWINGS

Reference is now made to FIG. 1 which shows a loom control and interrogation mechanism 10 which can be used by a human operator to manually identify and query any one of a number of loom stations, such as shown in FIGS. 2 and 4, which then responds by returning information relating to various conditions of the loom to the mechanism 10. Ten address lines emanate from the control mechanisms 10 and are labeled 11-20 inclusive. Each of these address lines connects to all of the loom stations which can be interrogated, and it is along these ten address lines that signals are sent identifying the loom chosen for interrogation. In this embodiment, each of the looms is represented by a binary number and each of the ten address lines carries a digit of that number so that, with 10 lines, control mechanism 10 can handle 1,023 different looms for other textile machines. Of course, the system can be simply expanded by adding additional address lines, each line added roughly doubling the number of looms which can be interrogated from one control mechanism 10.

Since the station address to be sent down the address lines — lines 11-20 in this embodiment is a binary number, this address can be encoded by simply closing those among the switches 21-30 on the lines on which one digit, for example, a binary one is to be sent, so that these lines can be connected to a storage battery and opening those among the switches 21-30 on the lines on which the other digit, for example a binary zero, it to be sent so that the potential on these lines will remain unchanged. In FIG. 1, for example, switches 22, 24, 25 and 29 are shown closed so that if the binary number of the loom chosen is read from left to right the station which will be interrogated by encoding this combination of open and closed switches will be 0101100010 or station 354 in base 10. Of course, a voltage pulse on the address lines can just as well represent binary zero and a lack of such pulses a binary one. The address lines can also be rearranged in any convenient order. However, for this embodiment it will be assumed that the presence of a pulse on any address line represents a binary one, and the absence of a potential of zero. After

the proper switches, in this example switches 22, 24, 25 and 29, have been closed, the on-off switch 40 is closed so that the positive terminal of the battery 42 is then connected to the lines down which a binary one travels and the binary address so formed on lines 11-20 travels to all of the loom stations. The other ends of lines 11-20 remote from mechanism 10 of course are connected to battery 42 or a similar source of potential or ground so that a pulse can move down the proper lines.

The information relating to operation of the chosen loom then returns to the loom control mechanism 10 down the lines 44, 46, 48 and 50 in the form of a potential which causes one or more of the light bulbs 52, 54, 56 and 58 to light provided certain conditions exist at the loom chosen. As described below, the lighting of these respective bulbs individually or in combination indicates that the loom is running, a warp out has occurred, a warp stop has occurred, or a filling stop is in progress. Although these few loom conditions comprise the vast majority of causes of loom stoppage, they are merely representative of the many possible loom conditions which can be sensed. The lighting of the four bulbs in FIG. 1 results because one side of the bulbs 52, 54, 56 and 58 is permanently connected to the negative terminal of the battery 42 and the other side of the bulbs is connected to the positive terminal of battery 42 or a similar source of potential when the above conditions are sensed.

The ten address lines which enable the mechanism 10 to handle 1,023 looms and the four return lines, together with any other lines such as may be added to convey information back to the control mechanism 10 or increase the number of looms interrogated, can be grouped in a single multi-conductor cable which then connects to each of the loom stations. Since the electrical environment of textile machines can be very noisy, shielding of this cable is desirable so that signals can be sent and received without substantial distortion.

Reference is now made to FIG. 2 which shows a loom station 60 with ten lines 61-70 inclusive attached respectively to the lines 11-20 so that the binary address sent from the control mechanism 10 down lines 11-20 enters the loom number gate 71. The gate 71 responds to the address carried on lines 11-20 with a given output signal only when the binary number received on lines 61-70 inclusive corresponds exactly to the binary address of the loom. One loom station, and only one loom station, responds to each address signal. This given output signal of the gate 71 can, for example, be a positive pulse, a high or low potential or any other suitable signal. Of course, if the binary address received in the loom number gate 71 does not correspond to the address of the loom station 60, then the given output signal is not produced and that loom station 60 does not respond.

This given output signal which indicates that the loom station 60 has been chosen and must respond is then applied to three logic gates, and a warp out switch via output line 72. If the loom running switch 73 which represents a sensor is closed indicating that the loom is running when the given output signal appears on line 72, the loom running gate 74 then produces a suitable output signal on the loom running output line 75 which is then passed to line 44. Of course, the loom running switch 73, as shown in FIG. 2, is merely representative

of a wide variety of electrical signal producing means which can be used to indicate that the loom is running. Similarly, the loom running gate 74 represents a variety of logical devices which are capable of reproducing an output which is a function of a plurality of inputs.

Similarly, the filling stop switch 76 may be of any type suitable to indicate that a filling stop is in progress or has occurred since the last interrogation. The filling switch 76 is connected as an input to the filling stop gate 77 along with the given output signal of the loom number gate 71 on line 72 so that the gate 77 produces a suitable electrical signal when the loom station 60 is being interrogated and the switch 76 indicates a filling stop is in progress. This signal is then applied to the filling stop output line 78 which is connected to return line 48.

The warp stop sensor also is represented by a switch 79. This sensor may be comprised of drop wires attached to the warp threads as discussed below or may be any other suitable type. The switch 79 then when closed, representing that a warp stop is in progress, produces a suitable electrical signal which is then applied as an input to the warp stop gate 80 along with the given output signal of the loom number gate 71 on line 72 resulting in an appropriate electrical signal on the line 81 which is communicated to the return line 50.

The manually or automatically operated warp out switch 82 serves to produce a signal indicating that the warp beam is being changed. This switch 82 also may be of any suitable type, including automatic, to produce an electrical signal indicating a warp out stop which is then applied to line 83 and then to line 46.

The gates 74, 77 and 80 can also be used to retain information so that, if the sensors sense a condition which begins after one interrogation and ends before the next, when interrogated the outputs of the respective gates 74, 77 and 80 actually indicate that the condition has occurred since the last interrogation. A similar gate can also be used with the warp out sensor if desired, but such a gate is not usually necessary since the duration of warp out stops is normally greater than the interval between interrogations.

Reference is now made to FIG. 3 which shows a card which can be used by a human operator to manually record the operation of each loom utilizing the control mechanism 10 shown in FIG. 1. Alternatively, automatic recording means such as an electrical recorder or counter can be used to mechanically perform the same function and a computer can also be used as a recorder to correlate the information as described in connection with FIG. 4.

First, the proper switches among switches 21-30 must be closed to create the binary pattern identifying the loom chosen to be interrogated, as described above. Then the on-off switch 40 is closed to send the address down lines 11-20 to each loom control station such as station 60 in FIG. 2. The loom station chosen then responds as described in connection with FIG. 2 and some or none of the light bulbs 52, 54, 56, and 58 will be illuminated.

If the loom chosen is running, then the light bulb 52 will light and the total running time as noted on the card in FIG. 3 can be increased by the time elapsed since the last interrogation. Next, the previous entry in the "IS LOOM RUNNING" block is erased and the

"YES" block is checked. Since the loom is running it is unnecessary to check any of the other lights since they all represent non-running conditions, and the next loom in order can be interrogated.

5 If, however, the loom running light bulb 52 does not flash, the "IS LOOM RUNNING" block is also observed. If the notation therein indicates that the loom was running during the last interrogation then the stop has occurred in the meantime. If, however the loom 10 was not in operation during the last interrogation, it may be assumed that the cause of stoppage has not changed and the next loom in line can be interrogated.

Should the light bulb 52 fail to light and the loom was 15 running during the last interrogation, the warp out stop light bulb 54 is next observed. If the warp out stop light bulb 54 is illuminated, the total warp out time is increased by the time elapsed since the last interrogation and any response from the remaining unchecked lamps can be safely ignored. However, if the warp out bulb 54 is not lit then the filling stop light 56 is checked and if lit then the new stop is recorded as a filling stop so that the number of filling stops on the card in FIG. 3 is increased by one. Next, if the filling stop bulb 56 is not lit 20 the warp stop light bulb 58 is checked and if the warp stop bulb 58 flashes, the new stop is recorded a warp stop and the number of warp stops is increased by one. Finally, if none of the four lights flash the stop is assumed to be a mechanical stop and is noted as such.

The card also contains areas wherein other useful information such as loom number, style of material being produced, etc. can also be recorded. The number of allowable warp, filling and mechanical stops can be recorded and constantly compared with the actual number.

At the end of every shift, the raw data on the cards can then be worked by machine or human to produce statistics setting forth overall weaving loom efficiency, as well as the efficiency of a given style, weave set, loom, or other classification. A list of those looms having excessive stops and the reason therefor can also be compiled. The used cards for each loom can then be filed to make a permanent record and replaced with a new set of blank cards to be used for the next shift.

Reference is now made to FIG. 4 which discloses an interrogating system including a particular loom station circuit which can be used in connection with a computer system as well as with a manually operated system. In this embodiment lines 91-100 exclusive, each of which serves to carry a digit of the binary address signal in the same manner as described in connection with FIG. 1, emanate from a computer 88 which serves to automatically choose the loom or other textile machine to be interrogated and to send out the proper binary interrogation signal identifying it. The computer then receives the information on loom conditions via return lines 102, 104, 106 and 108, each of which connects to all of the loom stations and to the computer via a logic sequential circuit 89 which is adapted to perform the sequencing function of examining the return lines described in connection with use of the card of FIG. 3. It will, of course, be understood that the loom stations 110, 112 and 114 shown in FIG. 4 can also be interrogated by the control mechanism 10 disclosed in connection with FIG. 1 as well as by the computer 88.

The computer 88 although preferably a general purpose digital computer may be of any suitable type and may be analog as well as digital in nature. Furthermore, as represented in FIG. 4, the computer 88 is intended to include whatever interface circuitry is needed or desired in connection with a particular model or kind of computer. Although in this embodiment the computer 88 is shown attached to three loom stations 110, 112, and 114, it will, of course, be obvious that since there are 10 interrogation lines the computer can interrogate at least 1,023 textile machines without adding additional lines and that more lines can be simply added to accommodate more machines.

The operation of the loom station 110 will now be described in detail. The address signal which is sent along the input lines 91-100 is brought into the loom station 110 on lines 121-130 inclusive. Since each of these lines represents a binary digit, some of the lines will bring a binary one into station 110 and others a binary zero. For the purposes of describing the operation of the loom station 110 it will be assumed that a high voltage is identified with a binary one and a low voltage with a binary zero. Each of the lines 121-130 is then applied to one of the inverting circuits 131-140, respectively, so that each digit or its inversion on all address lines 91-100 is available either on the input or output of the inverters 131-140. A number of switches 141-150 can then be manually or automatically connected to the input or the output of an inverter so that when the address sent down lines 91-100 corresponds with the address of loom station 110, the lines 151-160 which are then connected to the switches 141-150 all will carry a positive high voltage representing a binary one. In FIG. 4, switches 142, 145, 147 and 149 are connected to the inputs of the respective inverters and switches 141, 143, 144, 146, 148 and 150 to the outputs so that the address of the loom read from left to right 0100101010 or number 298 in base 10.

The signals on lines 151-160 are then applied to a NAND gate 161 which has a low output potential state only when all of the inputs are high. This condition is fulfilled only when the address of the loom station 110 corresponds with the address chosen by the computer 88 and sent along lines 91-100. Since in this embodiment an eight input NAND gate is used, three diodes 162, 163 and 164 are utilized to form an AND gate with three of the lines 158, 159, and 160, and the output of this gate applied as a single input to the NAND gate 161.

In this embodiment, the loom station 110 is capable of detecting four different and common conditions on a loom. The system is not intended to be limited to these conditions or to a loom and many other conditions can be sensed or additional information on loom conditions relayed to logic circuit 89 and the computer 88 by merely adding a new return wire for each new condition. Similarly, the system can be used equally well to sense a variety of other conditions on a variety of textile and other machines. However, these four conditions — loom running, warp stop, filling stop and warp out stop — represent the most useful and easily sensed information in a loom interrogation system.

First, when interrogated the loom station 110 is adapted to sense and so inform the computer 88 if the loom is operating. In this embodiment, this function is

accomplished by a sensor 165 which is mounted adjacent but separated from a gear 166 which rotates only when the machine is operating. Since almost all textile machines, and indeed all similar machines, have such a rotating gear, sensor 165 can be readily used and readily attached to many different machines. Furthermore, since such gears are usually covered and inaccessible, the sensing apparatus is protected from tampering by textile workers and from accidental damage. Furthermore, since the sensor 165 responds only to the gear movement and is normally mounted quite close to the gear 166, it cannot be easily fooled, for example, by grounding with a screwdriver or the like, so that it is virtually impossible for anyone to delude the computer 88 or manual operator into thinking the loom is running when it is not. Of course, the invention is not limited to any particular type of sensor and other types of sensors such as photoelectric, capacitive, ultrasonic and others can be used to sense whether the loom is operating.

The sensor 165 shown in FIG. 4 more particularly comprises a probe 170 mounted adjacent the gear 166, and a coil 172 associated with probe 170. This probe 170 serves to continuously sense the distance between itself and the gear 166, producing an electric signal which is a function of this distance. Since this distance is constantly changing when the gear 166 is in motion and the loom operating, a changing current is produced within the coil 172 whenever the gear 166 is in motion. This changing current produced by the motion of the gear 166 is then rectified and doubled by diodes 174 and 176 and capacitors 178 and 180 so that a direct current voltage is applied between the base and emitter of transistor 184. Since this base emitter voltage is negative, the NPN transistor 184 remains cut off as long as the gear 166 is turning.

Accordingly, while the gear 166 is turning, the collector of transistor 184 will be at the potential V_{cc} since no current can flow through the cutoff transistor 184. This collector voltage is then applied as a first input to the NAND gate 190, the potential V_{cc} representing a binary one. However, should the gear 166 cease rotating, no further changing current is produced in the coil 172 and the transistor 184 conducts because the base emitter voltage becomes positive due to the voltage dividing resistors 191 and 192. When this transition from non-conductive to conductive state takes place the input to the NAND gate 190 slips to a low potential approaching ground potential, a potential representing a binary zero.

The output of the NAND gate 161, which is low representing a binary zero only if loom station 110 has been chosen to be interrogated, is applied to a NAND gate 200 along with the positive potential V_{cc} , which represents a binary one. Therefore, while station 110 is being interrogated, and the output of NAND gate 161 accordingly drops to a low potential representing a binary zero, the output of the NAND gate 200 assumes a high potential representing a binary one. The output of gate 200 is then applied to NAND gate 190 along with collector voltage of transistor 184 as described above so that the output of NAND gate 190 during interrogation is low representing a binary zero only if the loom is running. While station 110 is not being interrogated, the output of gate 190 is, of course continuously high.

The output of NAND gate 190 is then applied to the loom running return line 108 via diode 202 and the information carried to the logic circuit 89 and then to the computer 88 as described below. If the signal detected on line 108 indicates to logic circuit 89 that the loom is running, then the logic circuit 89 provides a signal to the computer 88 indicating that condition on line 275 and disregards the other lines, just as the human operator of the apparatus in FIG. 1 ignores the other lights if the loom running bulb 52 is lit.

However, if a low signal representing that the loom is running is not received along line 108 the logic circuit 89 sequentially checks the other lines to determine the reason for the stop. While in the particular embodiment shown in FIG. 4 a warp out stop is checked first followed by a filling and a warp stop, no limitation as the order is intended nor required. If desired the conditions can be checked in any order. The operation of the logic circuit 89 is described in further detail in connection with the discussion of FIG. 5 below.

When station 110 is interrogated, line 106 assumes a low potential if a warp stop which takes place when a warp thread breaks has occurred since the last interrogation. Frequently, a drop wire is associated with each warp thread so that should any of the threads break the drop wire falls, completing a circuit which then signals that a warp thread has broken and causes the machine to cease operating. This warp stop sensor is represented in FIG. 4 by a switch 206 which is closed when a warp stop is in progress.

The closing of switch 206 completes a circuit path through the coil of solenoid 208, causing it to pull in and initiate a series of mechanical actions which result in the loom's being stopped. The switch 212 is so positioned on the loom that it is closed whenever the operating lever, or shipper handle, is in the running position. Switch 206, solenoid 208, and switch 212 are parts of the conventional warp stop motion of a loom. For the purpose of sensing the operation of the warp stop motion, a relay 214 is connected in parallel with solenoid 208 so that, should the switch 206 close, current will also pass through relay 214, shifting switch 216 from a high potential at V_{cc} to the low potential of ground.

Switch 216 is connected to one inout of a J-K flip-flop 217 which shifts its output along line 218 from a first to a second state whenever the switch 216 is connected to the low potential, for example ground. For the purpose of explanation, it will be assumed that the first state is a low potential and the second state is a high potential. After shifting from a low to a high output potential the flip-flop 217 remains in a high potential output state until it is reset as described below.

The output of flip-flop 217 along line 218 is then applied to the NAND gate 224, along with the output of the NAND gate 200, so that the output of NAND gate 224 is low representing a binary zero, only when station 110 is being interrogated and when the flip-flop 217 indicates that a warp stop has occurred since flip-flop 217 was reset last during the last interrogation. The output of NAND gate 224 is then applied to the warp stop return line 106 via diode 226.

The system is also adapted to determine if the stop which the high potential on line 108 indicated is taking place is a filling stop. A filling stop is sensed in this em-

bodiment by the closing of switch 230 which then connects the low input of ground to the input of the flip-flop 232 which operates in the same manner as flip-flop 217, shifting its output along line 240 from a low to a high output whenever switch 230 is connected to a low potential. This switch 230 may, for example, be a reed or similar switch inserted into a hole in a metal block which is then mounted on a loom. A magnetic member 234 is then attached to a movable member of the loom (not shown) so that, when the loom is stopped for filling, the magnetic member 234 is automatically positioned so as to cause the switch 230 to close and ground the input of flip-flop 232. This filling stop arrangement is fully described in connection with patent application, U.S. Pat. No. 3,437,799 entitled "Loom Stop Counter," filed Feb. 10, 1967.

When the switch 230 is closed, then the output of flip-flop 232 along line 240 assumes a high voltage representing a binary one and, remains in that high potential output state until the flip-flop 232 is reset as described below so that, regardless of whether or not the switch 230 opens after closing, the flip-flop 232 remembers any filling stops which occur between resets.

The output of flip-flop 232 is then applied to the NAND gate 250 along with the output of the NAND gate 200 so that the output of NAND gate 250 along line 252 is low only if a filling stop has occurred and station 110 is being interrogated. The output of NAND gate 250 is then applied to return line 104 via diode 260 so that a low potential on line 104 indicates that a filling stop has occurred since the last interrogation.

The flip-flops 217 and 232 are reset, shifting from the high to the low output states, whenever the reset inputs on lines 261 and 262 respectively, assume a low voltage. Resetting is accomplished during each interrogation since lines 261 and 262 are connected to the output of NAND gate 161 through a delay circuit comprising the capacitor 263 and resistor 264 so that the flip-flops 217 and 232 are reset after the information has been sent on return lines 102, 104, 106 and 108.

Flip-flops can also be added to retain information on warp out stop information if desired. However since warp out stops are of relatively long duration in this embodiment they are manually sensed by the loom operator who then closes the double pole single throw switch 265. Alternatively, automatic apparatus for performing this function can be used and a wide variety of switches substituted for switch 265.

In this embodiment the human operator manually closes the switch 265 which is represented as two ganged switches 269 and 270. The closing of switch 270 connects the output of NAND gate 161 to reply line 162 through isolating diode 272. When the output of gate 161 goes low as a result of the stations correct address being received, this low potential is applied as an input to line 102, indicating that a warp out stop is in progress. The closing of the switch 269 also serves to prevent anyone from operating the loom after the warp out stop has ended without manually returning switch 265 to its initial position. Closing switch 269 completes a circuit path through the coil of solenoid 208 causing it to pull in and initiate the same actions as in the same manner as occur when switch 206 closes and resulting in the stopping of the loom described above. Current also flows through relay 214 so that a warp stop is in-

dicated on line 106 as described above, but the logic circuit 89 or human operator disregards signals on line 106 if a signal is received on line 102.

Although NAND gates have been used in the detailed embodiment shown in FIG. 4, no such limitation is required, or intended. Any type of logical system can be used, including AND gates, relays or any other logical devices. However, NAND gates have a number of desirable properties including their ability to be used as universal logical blocks, their availability, and their ability to drive a number of other blocks directly, which make them especially desirable and useful.

Reference is now made to FIG. 5 which discloses detailed circuitry of the logic circuit 189 shown in FIG. 4, for performing the sequencing function performed by the human operator as described with the use of the card shown in FIG. 3. Line 108 which is at a low potential provided the loom is running is attached directly to the input of a NAND or other gate 273 which serves to invert the signal on line 108. The output of gate 273 is then attached to a monostable flip-flop 274 which responds to a high potential on its input by producing short pulse of voltage which is carried to the computer or manual operator on line 275. If the voltage applied to flip-flop 274 is high, causing flip-flop 274 to produce a short pulse, none of the other lines need be logically considered, since the loom is running.

The output of inverter 273 is then applied as one input to a NAND gate 276 via line 277 so that line 277 is at a low potential if the loom is not running. The other input to the NAND gate 276 is the warp out return line 102 which assumes a low potential output state only if the warp out sensing apparatus, which in FIG. 4 consists of a manual switch 265, indicates that a warp out stop is in progress. The inputs to the NAND gate 276 will be both at a low potential representing a binary zero only if a warp out stop is detected as being in progress and the loom is detected as not operating. The output of NAND gate 276 is then applied to another monostable flip-flop 278 so that the flip-flop 278 produces a short voltage pulse on the line 279 only when the output of gate 276 assumes a high potential representing a binary one. Therefore, a signal is produced on the warp out line 279 only if a warp out stop is detected and the loom is detected as not operating.

Next the filling stop return line 104 is checked to determine if a filling stop has occurred since the last interrogation. A filling stop can be indicated only if a pulse is not sent on lines 275 or 279. The filling stop line 104 is applied as a first input to the NAND gate 280 along with the output of gate 273 which represents the inverted voltage signal from line 108 and the output of NAND gate 282 which represents the inverted signal from line 102. All three signals to the NAND gate 280 will be at a low potential representing a binary zero only when a filling stop is sensed, the loom is not running, and no warp out stop is in progress, since signal on line 108 is high only if the loom is not running, the input to NAND gate 280 on line 283 is low only when a warp out is not occurring and the signal on line 104 is low only when a filling stop is occurring. The output of NAND gate 280 is then applied to a monostable flip-flop 284 via line 285 so that a voltage pulse appears on line 286 which is then conveyed to the com-

puter or human operator if a filling stop has occurred and only after the first two logical conditions — loom not running and warp out stop not occurring — have been satisfied.

5 After lines 108, 102 and 104 have been logically examined, the warp stop condition is checked. An output pulse is produced on line 290 provided that a warp stop is sensed and none of the other three conditions have been. The NAND gate 292 has four inputs — line 106 10 which assumes a low potential representing a binary zero only when a warp stop is in progress, line 293 which is the inversion of the signal on line 108 so that line 293 carries a low potential only when the loom is not running, line 294 which is the inversion of the signal on line 102 and which likewise carries a low potential signal only when no warp out has occurred since the last interrogation, and line 295 which carries the inversion of the signal on line 104 and which carries a low potential signal only when a filling stop has not occurred since the last interrogation. The output of NAND gate 292 is then applied to monostable flip-flop 296 along line 297. The application of a high potential signal to flip-flop 296 then produces an output pulse on line 290 indicating that a warp stop is in progress.

If none of the above three causes for stoppage is detected and the loom has ceased operating, then a voltage pulse appears on line 298 which, by process of elimination, indicates a mechanical breakdown. The NAND gate 299 then has four inputs each of which represents the inverted signal on one of the lines 102, 104, 106, and 108. Since the potential of all these lines will be high if the loom is not running, a warp out stop is not in progress, a filling stop has not occurred, and a warp stop has not occurred, then all the inputs to NAND gate 299 will be at a low potential representing a binary zero when a mechanical failure occurs. The output of NAND gate 299 on line 301 then assumes a high potential causing the monostable flip-flop 302 to produce a voltage pulse which travels on line 298 to the computer 188 or human operator.

It is also possible to perform the same logical operations in a number of other ways. For example, the computer 188 can be given a set of instructions which it then follows to perform the logical sequencing function described. Alternatively, circuitry within each loom station or within the computer interface can also be used to perform the function of logic circuit 189.

Reference is now made to FIG. 6 which describes another embodiment of the invention whereby each loom station signals the computer only in the event that the loom stops. The computer or manual operator thus becomes a passive rather than active element in the system, since no sequential interrogation of the looms takes place. Furthermore, since during any given period far more looms will be running than not, a great amount of computer time can be saved by merely having the loom station notify the computer if it has ceased operating and indicate the cause of stoppage.

Since it is highly improbable that more than one loom will attempt to notify the computer at the same time, there is no necessity to deal with the possibility of simultaneous information on the lines from more than one loom. The information will be conveyed in a few microseconds so that any confusion will occur very infrequently. However, should it be desirable to prepare

for this eventuality, information retaining means can be associated with the respective loom stations to hold information until the respective lines are clear.

In the embodiment shown in FIG. 6, lines 311-320 inclusive, carry the address of the loom station in the same way as described in connection with FIGS. 1-4 and lines 311-320 connect to each respective loom station. Similarly, return lines 321, 322 and 323 return information to the computer 324 in the same manner as lines 102, 104, 106 and 108, and also are connected to all of the other loom stations. Although only stations 325, 326, and 327 are shown, it is, of course, obvious that the system can be used with many more looms.

The system shown in FIG. 6 differs from that shown in FIGS. 1-4 in that instead of responding to an interrogation signal which corresponds to the address of the loom, a loom station responds to a stoppage by applying its address to the address lines 311-320 to indicate that the loom has stopped operating and further supplies information signals to the respective return lines 321-324 to indicate the cause of stoppage. When the stoppage has ended the loom station once again applies its address to the address lines 311-320 to indicate stoppage has ended.

The operation of loom station 325 will now be detailed. As described in connection with FIG. 4, the loom running sensor 330, which, for example, operates by sensing the motion of a gear which rotates only during operation, produces an electrical signal which indicates whether the loom is running or not. Similarly filling stop sensor 332, warp stop sensor 334 and warp out sensor 336 produce electrical signals when these conditions are sensed. For the purposes of explanation it will be assumed that the signals produced are bilevel potential signals but no such limitation is intended nor required.

An amplifier circuit 340 serves to amplify the output of the sensor 330 and to produce a first output state when the sensor 330 detects motion and a second output state when it does not. Similarly, lines 342, 344, and 346 assume a first output state when respectively a filling stop is in progress, a warp stop is occurring and a warp out stop is occurring and a second output state when they are not. These conditions may be sensed in the manner shown in FIG. 4 or by any other suitable means. The output of the amplifier 340 is then applied to a logic gate 350 along with the signal on line 342 which indicates whether a filling stop is in progress, so that the logic gate 350 is enabled and produces a signal on line 352 only when the filling stop sensor 332 detects a filling stop and the loom running sensor 330 indicates the loom is not operating. The output of gate 350 on line 352 is then applied to a monostable flip-flop 354 which then produces a short pulse which is passed through the diode 356 and return line 323 to be carried to the computer 324. A short pulse on line 323 then indicates that a filling stop has occurred.

Similarly, warp stop sensor 334 applies a suitable electrical signal to line 344 when this condition is sensed. The output on line 344 is then conveyed to another logic gate 360 along with the output of the amplifier 340 so that an output signal on line 362 results only when gate 360 is enabled, i.e. only when the loom running sensor 330 detects that the loom is not running and the warp stop sensor 334 detects a warp stop. The

signal on line 362 is then applied to another monostable flip-flop 364 which then produces a short pulse which is applied to the return line 322 via diode 366.

In addition, warp out stops are sensed when warp out sensor 336 produces an output signal on 346. The signal on line 346 is then applied as an input to logic gate 370 along with the output of amplifier 340, so that the output of logic gate 370 on line 372 causes monostable flip-flop 374 to produce a short pulse which is conveyed to line 321 and hence to the computer 324 via diode 376.

The respective outputs of logic gates 350, 360, and 370 are then applied to another logic gate 380 which produces an output signal if any of the three gates are enabled so that the gate 380 is enabled if any of the three stoppage conditions are sensed and the loom is not operating. The output of the logic gate 380 on line 382 is then applied to another monostable flip-flop 384 which produces a short pulse if the gate 380 is enabled. This pulse is carried to the encoder 386 on line 388. The encoder 386 then applies a potential to some of the address lines 311-320 to create a binary pattern which identifies the loom station sending the information. The computer 324 or manual operator then receives the address of the stopped loom on lines 311-320 as well as the reason for the stoppage on lines 321-323.

After the loom is back in operation the logic gates 350, 360 and 370 will be disabled as will the logic gate 380. The output of amplifier 340 is also applied through a delay network 390 to a logic gate 392 along with the output of the logic gate 380. This gate 392 is enabled only when the logic gate 380 is disabled and when the amplifier 340 indicates that the loom is not operating. These two conditions are satisfied briefly after the loom starts and until the signal from amplifier 340 passes through the delay circuit 390. When these two conditions are satisfied, then the output of the logic gate 392 on line 394 causes monostable flip-flop 384 to produce another short pulse on line 388 to cause the encoder 386 to once again apply the pattern of pulses on lines 311-320 which identify the loom.

The computer or manual operator knowing that the stopped loom is not operating can assume from receiving the address of the stopped loom a second time that the loom is now operating. The computer will, of course, be adapted to assume that the loom remains stopped until the loom number is received without corresponding information on lines 321-323. However if the cause of loom stoppage was not one of three sensed causes, such as a mechanical failure, the gate 392 will cause the flip-flop 384 to produce a pulse and thus encode the address lines 311-320 as soon as the loom stops. Since the address is not accompanied by signals on return lines 321-323 the computer can assume a mechanical failure is taking place. When the loom is restarted the computer 324 will have to be notified by manually encoded information as described below or otherwise since the address will not be sent again upon restarting.

The system is also adapted to supply manual stop information of the type which the loom fixer or other personnel might enter relating the type of stop or the like. This information would be in the form of a coded signal directly following the address which the loom sends upon restarting. Information can be manually entered

on encoder 396 while the loom is stopped, and when the loom starts again causing the address of the loom to be sent on lines 311-320, the output of the delay circuit 390 also triggers a monostable flip-flop 398 which produces a short pulse which is carried on line 399 to encoder 396 causing the encoder 396 to apply the coded signal to lines 311-320 following the address signals which have been applied by encoder 396. Delay circuit 400 then serves to clear the manual encoder 396. The computer 324 or manual operator will know that such information can follow an address and will look for it. Since loom addresses will be sent relatively infrequently, little confusion arises between addresses of other looms and manually encoded information.

Reference is now made to FIG. 7 which describes another embodiment of the invention whereby each of the loom station signals the computer only in the event that the loom with which it is associated stops. As in the embodiment shown in FIG. 6, and described above, the computer or manual operator is a passive element in this system rather than playing an active role, sequentially interrotating the looms as in the embodiments shown in FIGS. 1-4. As pointed out above, a passive arrangement results in a considerable amount of savings in computer time since, during any given period, far more looms will ordinarily be running than not.

In this embodiment, as in the embodiment shown in FIG. 6, there is no real necessity to deal with the possibility of simultaneous notification by more than one loom on the same respective lines since the information as to stoppage can in fact be conveyed in a short span of time compared to the average time between stoppages so that it is possible to use the same common lines for all of the loom stations without frequent confusion due to attempted simultaneous transfer of information.

In the embodiment shown in FIG. 7, address lines 410 - 419 carry a binary address signal in the same manner as the address lines 91-100 in FIG. 4 and the address lines 311-320 in FIG. 6. However, in contrast to the system shown in FIG. 4 whereby the address signal carried on the lines serves to query the station so identified, requiring an answer as to whether the loom has stopped, lines 410 - 419 do not carry the address of a stopped loom to the computer 422 in response to interrogation by the computer 422 but rather in response to the stoppage itself.

As in the embodiment shown and described in connection with FIG. 6, the address lines 410-419 carry the address of the stopped loom and reply lines 423, 424 and 425 carry specific information relating to the cause of the stoppage. In addition, code lines 428, 429 and 430 carry coded information which may be manually entered by the operator, for example to notify the computer 422 that he has taken some affirmative action or has recognized some special condition which needs to be dealt with in a special manner. Although only three loom stations, namely loom stations 432, 434 and 436, are shown connected to the computer 422, the system obviously can be used with many more looms merely by connecting additional loom stations to the respective address, reply and code lines in the same manner as shown.

The operation of a loom station 432 will now be discussed in detail. The loom running sensor label 440

produces an electrical signal which indicates whether the loom is running or not. For this embodiment, it will be assumed that the signal is simply a bilevel signal with one level indicating that the loom is running and the other that the loom is stopped. As set forth in connection with FIG. 4, the sensor, 440, can operate by sensing the motion of a gear on the loom which rotates only during operation. Alternatively, any suitable system for sensing whether a loom is in fact operating or not and producing a suitable electrical signal can be used, for example a relay connecting a potential to the line 442, for example the 12 volts circuit of the loom, while the loom is running and disconnecting it whenever the loom ceases operating, or vice versa.

The electrical signal indicating whether or not the loom is operating is then fed on line 442 via diode 444 to a monostable multivibrator 446 which is of the type which responds to a change in the level of the input signal level with an output pulse. Each stopping and starting of the loom associated with loom station 432 results in such a change in the signal level applied to multivibrator 446 so that multivibrator 446 responds to each starting and stopping by producing a single output pulse of predetermined height and duration on line 447 regardless of the magnitude or duration of the signal input to multivibrator 446. Multivibrators of this type, such as multivibrator 446, are, of course, well known in the art and need not be described in detail.

The output of multivibrator 446 is then applied to the base of a transistor 450 on line 452. The collector of transistor 450 is connected to a positive source of potential V_{cc} via a resistor 454 while another resistor 456 connects the base and grounded emitter of the transistor 450. The transistor 450 and the values of resistors 454 and 456 are chosen so that the transistor 450 is driven into conduction during the time the pulse from multivibrator 446 is received at its base and remains in a state of non-conduction during the absence of such a pulse.

Whenever the transistor 450 begins to conduct, the collector of transistor 450 shifts from a potential of V_{cc} to approximately ground thereby changing the potential of the address lines connected to that collector so that a pulse is sent down those lines. The pattern of pulses on some lines and none on others, representing the address of a given loom station, is then determined by which of the address lines are connected to the collector of transistor 450 and which are not so that, when the transistor 450 begins to conduct, a signal which can either indicate a binary zero or one is sent down those lines that are so connected and no signal which represents the opposite digit on those lines which are not so connected. Thus for loom station 432, lines 411, 412, 414, 415, 416 and 419 are connected to the collector of transistor 450 via isolating diodes of 460, 461, 462, 463, 464 and 465. If the presence of a signal on a given line is interpreted as a binary one, the address of loom station 432 reading from bottom to top would be 0110111001 or 441 expressed in base 10. This station address is then impressed on address lines 410 to 419 as described, whenever the loom sensor 440 senses that the loom has either stopped or started.

The apparatus shown in FIG. 7 is also capable of indicating to the computer whether the cause of stoppage is due to a warp stop or a filling stop. If a warp stop oc-

curs, the warp stop sensor 474 produces an electrical signal which is suitable to trigger another monostable multivibrator 476 which then responds by producing a pulse of a given amplitude and duration which is then conveyed to the logic gate 478 via line 480 along with the output of multivibrator 446 on line 481. However, multivibrator 476 only responds to the change in signal, indicating a warp stop and does not produce a pulse when the warp stop condition ceases to exist. Logic gate 478, which may be a NAND gate, responds to the temporal coincidence of the pulses from multivibrators 446 and 476 with a suitable signal indicating that a warp stop has occurred. Since it is possible to sense a warp stop 20 to 300 milliseconds before the loom stops depending on the position of the loom when the warp breakage occurs with the result that the pulse from multivibrator 476 may occur before the pulse from multivibrator 446, it is desirable that the pulse produced by multivibrator 476 be of substantially longer duration than the signal produced by multivibrator 446. A duration of about 0.5 second has been found satisfactory for the pulse produced by multivibrator 476. In the embodiment shown in FIG. 7, NAND gate 478 responds to the coincidental presence of both pulses by grounding line 424 via diode 482. Line 424 is connected to the computer 422 so that the computer 422 upon receiving, at the same time, an appropriate signal on line 424 and an address of a particular loom station can assume that that station is undergoing a warp stop.

Similarly, filling stop sensor 496 produces a suitable electrical signal to trigger monostable multivibrator 498, producing an electrical pulse of a given pulse and duration, whenever a filling stop is sensed. This pulse from multivibrator 498 is then conveyed to logic NAND gate 499 on line 500 at approximately the same time that the pulse output of multivibrator 446 is also applied to logic gate 499 on line 502. Since a filling stop may be sensed somewhat before a stop is, it is also desirable that the duration of the pulse produced by multivibrator 498 exceed substantially the duration of the pulse produced by multivibrator 446. The output of logic gate 499 on line 504 is then applied to the line 425 and then to the computer 422 via isolating diodes 506. In the embodiment shown in FIG. 7, NAND gate 499 then responds to the coincidental presence of the two pulses by producing a suitable signal indicating that a filling stop is occurring, for example by grounding line 425. From the receipt of a loom address and a signal on line 425 at the same time, the computer recognizes that a filling stop is occurring on the identified loom.

Whenever the loom restarts, the loom sensor 440 again shifts its output signal level and line 442 once again causing the multivibrator 446 to produce another pulse identical to the pulse produced when the loom stopped. The transistor 450 once again enters a state of conduction which continues as long as the pulse persists, grounding the appropriate lines among the address lines 410 - 419 so that a binary signal pattern representing the address of loom station 432 is once again conveyed to the computer 422. Since the computer 422 is aware that the loom is stopped, it recognizes that the receipt of this further signal means that the loom so identified is once again running normally.

Although not necessary, it is desirable that the signal indicating a start and the signal indicating a stop be different so that the computer 422 can correct itself in the event one signal is missed. In this embodiment, this difference is provided by the presence of a signal on line 423 only when the loom starts. This is accomplished by connecting the output of the multivibrator 446 and of the sensor 440 to a logic gate 507 which responds with an output signal only when the output pulse from multivibrator 446 is received coincidentally with an output of sensor 440 indicating that the loom is running. These two signals are produced at the same time only after the loom restarts and not upon stopping so that a signal applied on line 423 via diode 508 gives the computer reassurance that the loom identified from the pattern on address lines 410-419 has restarted.

After the loom has stopped, it is possible to encode information onto the manual encoder 510 which indicates to the computer either that certain action had been taken or that a certain condition is present. In the embodiment shown in FIG. 7, seven possible coded information signals can be sent to the computer on lines 428, 429 and 430 by rotating a three-pole 8 position switch 511 which is conventionally wired for octal to binary conversion to one of the eight possible positions. The three manual encoding lines 428, 429 and 430 are each connected to four of the positions on each individual switch 512, 513 and 514 as shown, so that in each different position to which the switch 511 can be rotated the wipers 515, 516 and 517 are connected or not connected to a different combination at lines 428, 429 and 430. Isolating diodes 520, 522 and 524 connect the switches 512, 513 and 514 to the appropriate, lines 428, 429 and 430.

The information which has been encoded on switch 511 is then sent to the computer automatically when the loom restarts or manually closing a switch 530 which, for example, may be of the push-button type. The closing of switch 530 connects the positive potential of V_{cc} to the input of the monostable multivibrator 446 so that the address of loom 432 is sent to the computer to 422 in the same manner as if the loom had just stopped or restarted. Since the voltage at the input of multivibrator 446 changes when the switch 530 is closed only when the loom is stopped, closing the switch while the loom is running has no effect. No accompanying signal on line 423 is received by the computer 422 so no possibility of interpreting the receipt of the address as a start exists.

The closing of switch 530 also connects the positive potential V_{cc} to a logic gate 532, for example a NAND gate, along with the output of monostable multivibrator 446 so that when an output pulse is produced on line 447, the output of NAND gate 532 on line 534 assumes a low potential, for example ground. The grounding of line 534 grounds the wipers 515, 516 and 517 and some or all of the lines 428, 429 and 430 depending on the position in which switch 511 is set so that an information signal is carried to the computer 422.

Similarly, the logic gate 532 responds to the starting of the loom by grounding line 534 and thereby sending the appropriate information signal down lines 428, 429 and 430. When the loom, in the embodiment shown in FIG. 7 starts, the output of loom sensor 440 shifts to a high level triggering multivibrator 446 so that both in-

puts to logic gate 532 are high with the result that gate 532 grounds line 534. However, when the loom stops the level of the output of sensor 440 shifts to a low level to which gate 532 does not respond and no signals are sent down lines 428-430.

One three-pole switch can encode eight numbers, or seven if zero is omitted. If more information codes are desired three more wires connected to another three pole switch can be added to provide a total of 64 numbers. More numbers can be made by adding additional wires and switches in the same manner.

Reference is now made to FIG. 8 which shows a multi-level addressing system for use in an interrogation system such as described in the above embodiments and to FIG. 9 which shows in detail a master station for use in a system such as illustrated in FIG. 8. In the system FIGS. 8 and 9 in contrast to the embodiments of FIGS. 1-7, the individual loom stations are associated in groups and the groups are organized into master groups. If, at any time, it is necessary, or desirable to accommodate a larger number of stations to an existing system, these master groups can themselves be organized into even larger groups and this form of organization can be extended as far as desired to accommodate any necessary growth in the system. The number of units in each group at any level is, of course, governed by the length of the level address, and it has been found convenient to use a four-digit binary address and correspondingly four lines to each level, each carrying one binary digit.

Referring to the embodiment illustrated in FIG. 8, three first level master stations 600, 602 and 604 are shown attached to the first level address cables 606 and it will be understood that normally at least several other first level stations will be attached to cable 606 in the same fashion. In this particular embodiment, four lines, each capable of carrying one binary digit, preferably comprise the first level address cables 606, and thus up to 15 master stations, such as 600, 602 and 604 can be attached to the first level cables 606.

Each master station, for example, station 600 which is illustrated in detail in FIG. 9, is made up of decoder circuitry and logic circuitry, station 600 including decoder circuitry 610 and logic circuitry 612. Decoder 610 responds to a binary address on first level cables 606 by producing an output on line 614 which causes logic circuitry 612 to pass a following or essentially simultaneous address on the second level cables 616 to the set of master stations, including stations 618, 620 and 622, which are among the second-level master stations associated with the first-level master station 600. Thus each of the stations connected to the master first-level station 600, of which station 618, 620 and 622 are illustrated in FIG. 8, receives the output of logic circuitry 612, which is the address transmitted from computer 624, on second-level cables 616.

Each of the stations 618, 620, 622 and the other stations associated with the master station 600 are preferable identical in construction to master stations 600, 602 and 604 and, as shown in FIG. 8, master station 618 is similarly comprised of decoder circuitry 626 and logic circuitry 628. As in station 600, decoder 626 responds to one particular address transmitted through logic circuitry 612 from the second-level cables 616. When the address of station 618 corresponds to the ad-

dress transmitted through logic circuitry 612, then decoder 626 produces a signal on output line 630 which is transmitted to logic circuitry 628 which then permits the third-level address on cables 632 to be transmitted through logic circuitry 628.

In the embodiment of the invention illustrated in FIG. 8 a group of individual machine data stations, such as shown in FIGS. 4, 6 and 7, are associated with each of the second-level master stations 618, 620 and 622. Three machine stations 640, 642 and 644 are shown associated with the second level master station 618 so that when logic circuit 628 is activated by an output on line 630 to pass the address, promulgated by the computer or other operator down line 632, to line 650 and to each of the machine stations 640, 642 and 644 the machine station so identified responds by transmitting the data back to the computer or other recorder on separate line 651 as in the embodiment of FIG. 4 or in any other suitable manner.

Thus the first address transmitted down cables 606 designates one master station, for example, master station 600. The second address transmitted down the second-level cables 616 is passed through the master station so identified to a plurality of similar second-level master stations which receive the second-level address only when the master station above them has been enabled in response to the first address on cables 606. Finally, the master station, which is identified by the address on the second level cables 616 permits the address on the third level cables 632 to be passed through it to a group of machine station which are associated with that second level master station and the machine station so identified by the signal on third-level cables 632 responds in the fashion discussed above.

FIG. 9, in particular, shows master station 600 which is typical of the master stations illustrated in the system, including stations 600, 602, 604, 618, 620 and 622. In FIG. 9, the first-level cables 606 are comprised of four individual cables 652, 654, 656, and 658 which each carry a binary digit from computer 624 or other interrogating device or operator. A ground level might indicate one binary digit and a positive voltage, for example, of five volts might indicate the other. Each of the lines 652, 654, 656 and 658 is connected to conventional inverters 660, 662, 664 and 666. Associated with each of the conventional inverters 660, 662, 664 and 666 are pairs of manually operable or permanently fixed ganged switches 670, 672, 674 and 676 respectively. As in the embodiment of the invention illustrated in FIG. 4, these switches can be opened and closed in a unique pattern which will provide that all for inputs to NAND gate 680 from the outputs of the inverters 660, 662, 664 and 666 will be at a "one" level only when the pattern of high and low levels on input lines 652, 654, 656 and 658 uniquely represent the address of station 606. Thus, NAND gate 680 will produce a "zero" output only when all of the four input conditions are "one" and this occurs only when station 600 is being addressed.

The output of NAND gate 680 on line 682 is then inverted by a conventional inverter 684 and the output of the inverter 684 is transmitted as one of the two inputs to each of the NAND gates 686, 688, 690 and 692. Each of the NAND gates 686, 688, 690 and 692 also

receives one of the four binary digits making up the address transmitted by the computer or manual operator 624 at the level immediately below the level of the address received by the inverters 660, 662, 664 and 666. In the embodiment of FIG. 9, inverters 686, 688, 690 and 692 receive the second-level cables 616 of FIG. 8 comprising lines 700, 702, 704 and 706. Thus, none of the NAND gates 686, 688, 690 or 692 produces an output until the decoder 610 responds to an address on first-level cables 606. The output of NAND gates 686, 688, 690 and 692 is inverted by conventional inverters 710, 712, 714 and 716 respectively so that the output of logic circuitry 612 on lines 720, 722, 724 and 726 is the same as the signals on lines 700, 702, 704 and 706 when the decoder 610 has responded to an address which matches the address set in the decoder 610 by the pattern of open and closed switches 670, 672, 674 and 676.

This particular arrangement has been found to be particularly advantageous as an addressing system since it utilizes fewer wires in the interconnecting cabling and fewer gates in the decoding circuitry of the machine station. Moreover, it is adaptable for systems of any size and an expansion of an initially small system is especially simple. Since only four address inputs are required for each station instead of ten as the embodiment illustrated above, one hex inverter normally required in those embodiments is eliminated and the internal wiring at each machine station is substantially simplified. While the master stations do initially appear to add to the total number of assemblies required for a given installation, this is not determinative since, in an embodiment as illustrated in FIG. 4, address amplifying stations for each group of 12-16 machine stations are frequently employed in order to make sure that each station receives a suitable address signal to which it can respond.

The above embodiments are merely examples of the invention and many modifications and changes are possible without departing from the scope of the invention. The invention can be practiced with many other types of machines and is not intended to be limited to textile machines. Accordingly, the scope of the invention is limited only by the scope of the appended claims.

What is claimed is:

1. A textile machine operation sensing system for conveying data relating to the condition of a given textile machine from each textile machine to recording means comprising:

a plurality of coding lines connecting each textile machine to each other textile machine and to said recording means for carrying coded address signals, each said coded signal representing a particular textile machine,

coding means for producing said address signals and applying said address signals to said coding lines, a plurality of condition sensing devices associated with said machines for producing electrical signals containing information on the condition sensed, encoding means associated with each said station for receiving manually entered information, means for connecting said encoding means to said recording means,

at least one return line connecting each textile machine to each other textile machine and to said recording means, for carrying at least some of said electrical signals, and

5 logic means associated with each textile machine and connected to said return line for applying said electrical signals to said return line approximately at the time said coding means produces an address signal corresponding to the address of the textile machine with which said logic means is associated.

2. A system as in claim 1 wherein said textile machine is a loom and wherein said plurality of condition sensing devices includes a first condition sensing device associated with each loom for producing a given electrical signal if the loom is operating, a second condition sensing device associated with each loom for producing a given electrical signal if a warp stop is occurring, a third condition sensing device associated with each loom for producing a given electrical signal if a filling stop is occurring and a fourth condition sensing device associated with each loom for producing a given electrical signal if a warp out stop is occurring.

20 3. A system as in claim 2 including a first return line for carrying signals produced by said first device, a second return line for carrying signals produced by said second device, a third return line for carrying signals produced by said third device, a fourth return line for carrying signals produced by said fourth device, and logic means connected to said first, second, third and fourth return lines for disregarding the signals on said second, third and fourth return lines unless the signal received on said first line indicates said machine is not operating.

30 4. A system as in claim 1 further including at least a single manual encoding line connecting each said manual encoding means to said recording means and to each other of said manual encoding means.

5. A system as in claim 1 including a plurality of said 40 manual encoding lines each carrying a binary digit.

6. A system as in claim 1 wherein said manual encoding means includes a ganged switch having an individual switch associated with each said manual encoding line for connecting or disconnecting that line to a source of voltage to indicate the binary digit encoded on that line.

45 7. A textile machine condition sensing system for conveying electrical information signals produced by a plurality of condition sensing devices associated with a plurality of textile machines to interrogating means comprising:

a plurality of address lines connecting each machine to each other machine and to said interrogating means for carrying coded address signals from said interrogating means, each said address signal designating a particular machine which is to reply, decoding means associated with each said machine and connected to said address lines for producing a given electrical output signal when said address signal designates that the machine is to reply, at least one return line connecting each machine to each other machine and to said interrogating means for conveying said electrical information signals from said condition sensing devices to said interrogating means, encoding means associated with each said station for receiving manually entered information,

means for connecting said encoding means to said recording means, and logic means associated with each said machine and connected to said return line for applying said electrical information signals to said reply line when said decoding means produces said given output signal.

8. A system as in claim 7 wherein said address signal is a binary signal and each said address line carries a digit of said binary address signal.

9. A textile machine in combination with the system of claim 7.

10. A system as in claim 8 wherein said textile machine is a loom, one of said devices is associated with each loom and said one of said devices produces a first electrical signal while the loom with which it is associated is operating, and a second electrical signal while the loom with which it is associated is not operating.

11. A system as in claim 10 wherein a second of said devices is associated with each loom and said second of said devices produces a first electrical signal if a filling stop is occurring and a second electrical signal if a filling stop is not occurring, a third of said devices is associated with each loom and said third of said device produces a first electrical signal if a warp stop is occurring, and a second electrical signal if a warp stop is not occurring, and a fourth of said devices associated with each loom and said fourth of said devices produces a first electrical signal if a warp out stop is occurring and a second electrical signal if a warp out stop is not occurring.

12. A system as in claim 7 further including addressing means for applying said coded address signals to said coding lines and wherein said addressing means includes a source of electrical potential, and a plurality of switches having an open and closed position and each said switch having one side connected to said source and the other side to one of said address lines so that the electrical potential of said source is applied to the address lines connected to the closed switches, thereby forming a binary pattern on said address lines.

13. A system as in claim 7 further including means for recording the signals on said return line and wherein said recording means includes a light bulb attached to each said return line so that a first light bulb is lit when said first signal is applied to said first return line, a second light bulb is lit when said second signal is applied to said second return line, a third light bulb is lit when said third signal is applied to said third return line, and a fourth light bulb is lit when said fourth signal is applied to said fourth return line.

14. A system as in claim 7 further including an apparatus for examining electrical information received on said at least one return line from one of a plurality of textile machines, said information including a first electrical signal from a first condition sensing device associated with said one machine indicating whether said textile machine is operating or not operating and at least a second electrical signal from at least a second condition sensing device associated with said one machine indicating the cause of non-operation of said one machine when said one machine is not operating, comprising logic means connected to said return line for receiving said first and second signals and for disregarding said second signal provided said first signal indicates that said machine is in operation.

15. A system as in claim 7 further including: a first condition sensing device associated with each machine for producing a first electrical signal when the machine with which it is associated is operating and a second electrical signal when the machine with which it is associated is not operating,

at least a second condition sensing device associated with each machine for producing an electrical signal which indicates the cause of non-operation of the machine with which it is associated when that machine is not operating,

means connecting said at least single return line to said first and second devices, and logic means connected to said return line and to said recording means for disregarding the signal received from said second device provided said first signal is received from said first device.

16. A textile machine as in claim 15 including a third condition sensing device associated with each said machine for producing a first electrical signal when a warp out stop is occurring and a second electrical signal when a warp out stop is not occurring, and a fourth condition sensing device dissociated with each said machine for producing a first electrical signal when a warp stop is occurring and a second electrical signal when a warp stop is not occurring and wherein said machine is a loom, said second device produces a first electrical signal when a filling stop is occurring and a second electrical signal when a filling stop is not occurring, and said logic means disregards the signals produced by said second, third and fourth devices and records that the machine is operating provided the signal received from said first device indicates that said machine is in operation, disregards the signals produced by said fourth and second devices and records that a warp out stop is occurring provided that the signal from said first device indicates that the machine is not in operation and the signal from said third device indicates that a warp out stop is occurring, disregards the signal received from said fourth device and records a filling stop provided the signal received from said third device indicates that a warp out stop is not occurring, the signal from said first device indicates the machine is not in operation and the signal from said third device indicates that a filling stop is occurring, records a warp stop provided the signal received from said fourth device indicates a warp stop is occurring, the signal from said first device indicates the machine is not in operation, the signal from said second device indicates that a filling stop is not occurring and the signal from said third device indicates that a warp out stop is not occurring, and records a mechanical stop provided the signal received from said first device indicates the machine is not in operation, the signal received from said second device indicates that a filling stop is not occurring, the signal received from said third device indicates that a warp out stop is not occurring and the signal from said fourth device indicates that a warp stop is not occurring.

17. An information gathering system for conveying data from a plurality of data gathering devices at a plurality of stations having a binary address to an interrogating system which produces binary signals, each of which is associated with a single station, comprising:

means for conveying said binary signals to each said station,

address decoding means at each station which produce a given output signal only when the binary signals received correspond to the address of the station,
 encoding means at each said station for receiving manually encoded information,
 first logic means associated with said station to cause said data gathering devices to convey said data to said interrogating means only when said decoding means produces said given output signal, and
 second logic means for conveying said manually encoded information to said interrogating means.
18. A method of interrogating a plurality of textile machines each having a plurality of condition sensing devices comprising the steps of:
 addressing each of said machines sequentially so that information signals from said devices are conveyed to recording means whenever a machine is interrogated, and
 manually encoding information onto a manual encoder so that the information in said encoder is conveyed to said recording whenever a machine is interrogated.
19. A method of conveying information from one of a plurality of textile machines to recording means comprising the steps of:
 manually encoding information relating to the operation of said machine onto a manual encoder associated with said one machine, and
 addressing each of said plurality of textile machines so that said information is conveyed to said recording means whenever said one machine is addressed.
20. A loom condition sensing system for conveying data on the condition of a given loom from a plurality of loom stations, each said station being associated with one of said plurality of looms to recording means comprising:
 a plurality of address lines connecting each station to each other station and to said recording means for carrying address signals, each address signal being identified with a different loom station,
 a loom running sensor associated with each said loom station for sensing whether or not a loom is operating and for producing an electrical signal having a first state when the loom is operating and a second state when the loom is not operating,
 a plurality of other sensors associated with each said station for sensing the cause of loom stoppage and producing electrical signals containing information relating to the cause of said stoppage,
 a plurality of coded signal lines connecting each said station to each other station and to said recording means for carrying coded signals manually applied relating to the condition of said station,
 encoding means associated with each said station for applying said address signals to said lines,
 a plurality of return lines connecting each station to each other station and to said recording means for carrying electrical information signals relating to the cause of loom stoppage to said recording means,
 a manual encoder for applying a coded signal to said coded signal lines, and
 logic means associated with each said station and electrically connected to said encoding means,

said manual encoder, said loom running sensor, and said other sensors for causing said encoding means to apply said address signal to said address lines when said given machine stops, for applying said information signals to said return lines when said encoding means applies address to said address lines, for causing said encoding means to apply said address signal to said address lines when said given machine starts, and for causing said manual encoder to apply said coded signal to said coded signal lines after said encoding means applies said address signal to said address lines.
21. A textile machine operation sensing system for conveying data relating to the condition of a given textile machine from each machine to recording means comprising:
 a plurality of master stations each connected to said recording means by a plurality of first level lines, a plurality of textile machine stations associated with each said master station, and connected to said recording means by a plurality of second level lines via the associated master station,
 manual encoding means at each said textile machine for receiving manually encoded data,
 means at each said master station for permitting the textile machine stations associated with that master stations to receive on said second level lines an address identifying one of those textile machine stations only when that master station receives on said first level lines an address identifying that master station, and
 means at each said textile machine station for transmitting information to said recording means when that textile station receives an address identifying it on said second level lines.
22. A system as in claim 21 further including a plurality of second master stations each connected to said recording means by a plurality of third level lines so that each of said second master stations has associated with it a plurality of the first master stations, those first master stations being connected to said first level lines via the associated second master station and means at each second master station for permitting the first master stations associated with that second master station to receive on said first level lines an address identifying one of those first master stations only when that second master station receives on said third level lines an address identifying that second master stations.
23. A system as in claim 21 wherein each said master station includes a decoder means for receiving an address from said first level lines and for producing a given output signal only when the address received is the address of that station and logic means for receiving the address on said second level lines and said given output signal and for passing said address on said second level lines to the textile machine stations associated with that master station only when said given output signal is received by said logic means.
24. A system as in claim 23 wherein each said address is a binary number with each line carrying one digit, wherein each said decoding means includes a plurality of inverters for each receiving a digit of said binary number on said first level lines, a plurality of switches associated with said inverters and having an open and closed position so that the pattern of open

and closed positions of said switches corresponds with the address of that master station and the output of all of said inverters is the same when the address on said first level lines is the address of that master station, and logic gate means for receiving the outputs of all of said inverters and producing a first output when all of the outputs of said inverters are the same and wherein said logic means includes a plurality of second logic gates

each having said first output as a first input and having a digit of said binary number on said second level lines as a second input so that said second logic gates pass said binary number of said second level lines to said textile machines stations associated with that master station only when said first output is received as said first input.
